(57) CLAIM

We claim the ornamental design for an optical disk recorder, as shown and described.

DESCRIPTION

FIG. 1 is a front perspective view of an optical disk recorder of the present invention;

FIG. 2 is a front view thereof;

FIG. 3 is a rear perspective view thereof;

FIG. 4 is a first side view thereof;

FIG. 5 is a second side view thereof;

FIG. 6 is a top view thereof;

FIG. 7 is a bottom view thereof;

FIG. 8 is an end view taken along the line 8-8 in FIG. 2;

FIG. 9 is a front perspective view thereof shown in an opened position; and,

FIG. 10 is a second side view thereof in an opened position. The broken line showing of optical disk recorder is included for the purpose of illustrating environment and forms no part of the claimed design.
